DESIGN FOR A GROMMET MEMBER

Edward E. Van Dyke, Van Nuys, Calif., assignor
to Douglas Aircraft Company, Inc., Santa
Monica, Calif.

Application June 21, 1940, Serial No. 93,169

Term of patent 7 years

To all whom it may concern:

Be it known that I, Edward E. Van Dyke, a citizen of the United States and a resident of Van Nuys, in the county of Los Angeles and State of California, have invented a new, original, and ornamental Design for a Grommet Member, of which the following is a specification, reference being had to the accompanying drawing, forming part thereof.

Figure 1 is an end view of a grommet member showing my new design; and

Figure 2 is a side elevational view thereof.

I claim:

The ornamental design for a grommet member, substantially as shown.

EDWARD E. VAN DYKE.
